United States Patent Office

Des. 216,940
Patented Mar. 24, 1970

216,940

BAIT CONTAINER OR SIMILAR ARTICLE

Alfred E. Stonedahl, 3633 Chinden Blvd.,
Boise, Idaho 83704

Filed Sept. 30, 1968, Ser. No. 13,793

Term of patent 14 years

Int. Cl. D2—08

U.S. Cl. D2—400

FIG. 1

FIG. 2

I claim:

The ornamental design for a bait container or similar article, substantially as shown.
